UNITED STATES PATENT OFFICE.

JAMES T. SEELYE AND LUTHER R. JACKSON, OF PUEBLO, COLORADO.

VULCANIZER.

Application filed February 5, 1923. Serial No. 617,079.

To all whom it may concern:

Be it known that we, JAMES T. SEELYE and LUTHER R. JACKSON, citizens of the United States, residing at Pueblo, in the county of 5 Pueblo and State of Colorado, have invented certain new and useful Improvements in Vulcanizers; and we do declare the following to be a full, clear, and exact description of the invention, such as will enable others 10 skilled in the art to which it appertains, to make and use the same.

Our invention relates to improvements in vulcanizers and the present disclosure thereof is directed to one designed primarily for 15 vulcanizing tire tubes, one object of the invention being to provide a vulcanizer which may be effectively operated from the battery current of the usual automobile.

Another object of the invention is to provide 20 for automatically moving the electrical heating element away from the work when the vulcanizer has reached a predetermined degree of heat, thus preventing burning of the tube or the patch being applied thereto.

25 A still further object is to provide a vulcanizer which may be inexpensively manufactured and marketed, yet one which will be highly efficient and reliable and may be operated with extreme ease.

30 With the foregoing in view, the invention resides in the novel subject matter hereinafter described and claimed, the description being supplemented by the accompanying drawing.

35 Figure 1 is a vertical section showing a vulcanizer constructed in accordance with our invention.

Figures 2 and 3 are horizontal sectional views, as indicated by lines 2—2 and 3—3 of 40 Fig. 1.

In the drawings above briefly described, the numeral 1 designates a C-clamp whose lower arm 2 is flat on its lower surface as indicated at 3 to rest upon a support, the 45 upper side of this arm being provided with an integral plate-like portion 4 which extends forwardly from said arm and also extends laterally in opposite directions therefrom, being preferably in the form of a circular disk. The forwardly projecting portion of this disk is provided with an integral depending flange 5 which extends transversely with respect to the arm 2 and is of a length to project oppositely beyond this 55 arm. The lower edge of the flange 5 is in the same plane with the surface 3 of the

arm 2, whereby they may both rest upon the same support to effectively hold the clamp against tilting.

Above the disk 4, is a circular plate 6 60 having a depending rim flange 7 which contacts with said disk, said disk, plate and flange, co-operating in forming a hollow base which contains a heating means described below. In the preferred form of construction, the upper side of the plate 6 is somewhat concave as indicated at 8 to taper the vulcanized patch to a feather edge and the lower side of said plate is provided with a boss 9 into which the upper end of a 70 screw 10 is threaded, this screw being passed loosely through an opening in the arm 2 and having its head countersunk in the lower side of said arm 2. An insulating washer 11 is interposed between the screw head and 75 the arm 2 and a disk of insulation 12 which rests upon the disk 4, is positioned between this disk and the boss 9, whereby to prevent excessive radiation of heat from the plate 6 to the lower portion of the clamp. 80 Also, as the insulating washer 11 is yieldable to some extent, it permits the necessary slight movement of the screw under temperature changes.

Any suitable heating element may be provided 85 within the hollow base for the purpose of heating the top plate 6 thereof. We prefer however to employ a suitably shaped resistance wire 13 mounted between disks of insulation 14 and having flexible terminals 90 secured to a pair of binding posts 15 which pass through and are insulated from the flange 7, the inner side of this flange also being preferably provided with an insulating lining as indicated at 16. The current 95 supply wires 17 which lead to the binding posts 15 may well pass through an opening 18 in the lower portion of the clamp 1.

For supporting the resistance wire 13 and its carrying disks 14, we have shown a plurality of inclined arms 19 having their lower ends secured upon the sheet of insulation 12, while their upper ends contact with and support the heating element formed by said parts 13 and 14. These arms are formed of 105 any desired materials having non-uniform coefficients of expansion, for the purpose of causing said arms to bend downwardly when a predetermined degree of heat is reached. It will thus be seen that when the device has 110 reached a predetermined temperature, the arms will bow downwardly and will thus

lower the heating element away from the plate 6, preventing burning of the patch or the work.

While any desired means may be employed for clamping the work against the plate 6, we prefer to employ the construction shown. A vertical clamping screw 20 is threaded through the upper arm of the clamp 1 and has its lower end swiveled in a central opening in a flat arched spring 21, the ends of this spring being extended outwardly as indicated at 22 and having slots 23. The ends 22 rest upon a clamping plate 24 and rivets or the like 25 pass through this clamping plate and are received in the slots 23 to connect the spring with the plate. By employing this construction, the work may be yieldably held in the desired manner. It will be seen that as the spring 21 is sprung downwardly by tightening of the screw 20, its ends will slide outwardly upon the clamping plate 24, this being permitted by the slot and stud connection between said spring and plate.

From the foregoing, it will be seen that we have provided a simple and inexpensive device by means of which tubes and other work may be effectively vulcanized without burning, particular attention being directed to the fact that the device may be well carried in the tool box or other appropriate part of an automobile and may be connected at will with one of the usual bulb sockets, for using current from the automobile battery for the purpose of operating the vulcanizer, it being understood that the current supply wires for the latter are equipped with a suitable plug for reception in the socket. We may further point out however that if desired, the plug may be dispensed with and the current supply wires suitably connected with the terminals of the battery, or when the device is used in a shop, other appropriate current supply means may be employed.

We may further point out that while the thermostatic arms have been shown for mov-

ing the heating element away from the top plate of the hollow base, a stationary heating element might be employed in this base, in which instance, it would be preferable to use any desired thermostatic cut-out for the current supply, operative when the vulcanizer has obtained a predetermined degree of heat.

We claim:

1. A vulcanizer comprising a plate and means for clamping the work against the same, a heating element movable toward said plate, and thermostatic means carrying said heating element and active under a predetermined degree of heat to move said element away from said plate.

2. A vulcanizer comprising a hollow base and means for clamping the work against one side thereof, a heating element in said base movable toward and from said side thereof, and thermostatic means carrying said heating element and active under a predetermined degree of heat to effect movement of said heating element away from said side of the base.

3. A vulcanizer comprising a plate and means for clamping the work against the same, a heating element movable toward and from said plate, and a plurality of arms longitudinally bendable under a predetermined degree of heat, one end of said arms supporting said heating element while the other ends of said arms are stationarily mounted.

4. A vulcanizer comprising a hollow base and means for clamping the work against the upper side thereof, a plurality of radially disposed inclined arms secured at their lower ends to the upper face of the bottom of said base, said arms being downwardly bendable under a predetermined degree of heat, and a heating element in said base supported by the upper ends of said arms.

In testimony whereof we have hereunto affixed our signatures.

JAMES T. SEELYE.
LUTHER R. JACKSON.
